(57) **CLAIM**

The ornamental design for an augmented reality head mounted display, as shown and described.

DESCRIPTION

FIG. 1 is a first perspective view of an augmented reality head mounted display showing our design;

FIG. 2 is a second perspective view of the augmented reality head mounted display showing our design;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is a first perspective view of the augmented reality head mounted display in use with an electric wire for reference; and,

FIG. 10 is a second perspective view of the augmented reality head mounted display in use with an electric wire for reference.

The broken lines in the drawings show portions of the augmented reality head mounted display which form no part of the claimed design.
